BOOK

John Patrick Murphy, Clifton Heights, Pa.

Application November 26, 1949, Serial No. 6,281

Term of patent 14 years

(Cl. D6—2)

To all whom it may concern:

Be it known that I, John Patrick Murphy, a citizen of the United States, residing at Clifton Heights, in the county of Delaware and State of Pennsylvania, have invented a new, original, and ornamental Design for a Book, of which the following is a specification, reference being had to the accompanying drawing, forming part hereof, in which:

Fig. 2 is a top or plan view thereof, the same being shown in opened condition.

I claim:

The ornamental design for a book as shown.

JOHN PATRICK MURPHY.
